Primary Examiner — David Muller(74) Attorney, Agent, or Firm — Minh N. Nguyen; Next IP Law Group LLP(57) CLAIM

The ornamental design for a pedicure spa, as shown and described.

DESCRIPTION

FIG. 1 is a perspective view showing the front, right side and top views of my new pedicure spa showing my new design; FIG. 2 is a perspective view showing the rear, left side and top views thereof;

FIG. 3 is a top plan view thereof;

FIG. 4 is a right side elevation view thereof; the left side elevation view is the same as the right side elevation view, such as that shown in FIG. 4;

FIG. 5 is a rear elevation view thereof; and,

FIG. 6 is a front elevation view thereof.

The broken line showing of parts of the drawings is included for the purpose of illustrating use and environment and forms not part of the claims.
